UNITED STATES PATENT OFFICE.

EDWARD W. WEBSTER AND CHESTER V. WEBSTER, OF DUBOIS, PENNSYLVANIA.

BALL COCK VALVE.

1,047,596.

Specification of Letters Patent. Patented Dec. 17, 1912.

Application filed April 22, 1912. Serial No. 692,443.

To all whom it may concern:

Be it known that we, EDWARD W. WEBSTER and CHESTER V. WEBSTER, citizens of the United States of America, residing at Du-
5 bois, in the county of Clearfield and State of Pennsylvania, have invented certain new and useful Improvements in Ball-Cock Valves, of which the following is a specification, reference being had therein to the accompanying drawing.

This invention relates to certain new and useful improvements in water closet valves, generally termed in the art "ball-cock valves", and the object of our invention is
15 to provide a valve of the above type which opens against pressure of water supplying the flush tank in which the valve is located by means of gravity acting upon a float in the tank when the water in the tank is re-
20 moved by opening the flush valve of the closet.

A further object of our invention is to provide in a device of the character set forth a construction for assisting the automatic self-closing of the valve by the force of pressure of the water in the line supplying the flush tank operating against the outside face of the inlet valve when the weight or
25 inertia of the float is overcome by the rising water in the tank.

It is a further object of our invention to provide a device of the type set forth above in which the valve will be held positively closed under the pressure of the water in
35 cases where the arm carrying the float should become broken, so that no water will run through the closet or be wasted under such conditions.

It is a still further object of the invention to provide a device of the above character in which means is provided for dispensing with the ordinary packing usually required, and novel means are employed in
45 lieu thereof for preventing the water dis-
charging over the tank walls when the valve is open.

With the above general objects in view, and also, others which will appear herein-
afters as the invention is more fully described
50 and claimed, the invention consists in the novel construction, combination and ar-
rangement of parts, a practical embodiment
of which is shown in the accompanying
drawings forming a part of this specifica-
55 tion; and wherein like numerals of refer-
ence will be employed to designate like parts

throughout the different views of said drawings, in which;

Figure 1 is a longitudinal sectional view of a ball cock valve in accordance with our invention, the valve being shown applied in position in a flush tank, the flush tank being largely broken away, the valve mechanism and the operating float being shown in open position in full lines, Fig. 2 is a transverse vertical sectional view of the valve partly broken away, taken on the line 2-2 of Fig. 1 and, Fig. 3 is a horizontal sectional view taken on the line 3-3 of Fig. 1.

The embodiment of the invention herein shown will be specifically described as to detail of parts, it being understood of course that such embodiment is susceptible to various changes in the details of construction without departing from the general spirit of our invention.

As herein shown, the embodiment consists of a valve body comprising a casing section 5 and a hollow stand section 6, made separate in order to allow for the assemblage of the parts. The hollow stand section 6 is usually located in an opening provided therefor in the bottom 7 of the flush tank to which the valve is applied, and is generally, as shown, provided with an annular flange as 8 to rest on said tank bottom. It is securely fastened in position in said opening by means of a flanged nut 9 threaded on the lower end of the stand section 6 and engaging the underneath face of the tank bottom. 90 A tail piece as 10 is usually coupled on to the stand section 6 by means of a suitable packing nut 11, connection being made with said tail piece, in any suitable or desired manner, with the water supply pipe (not shown.)

The casing section 5 of the valve body forms a receiving chamber 12 which discharges through a suitably disposed outlet 14, which is most conveniently located at one side of the chamber and has the walls of the spout preferably directed downwardly in order to prevent any splashing of the water against the walls of the tank, the top wall 14 forming an overhanging lip extending beyond the valve body, although such specific arrangement of the discharge spout is not essential to the successful working of the device. It is usually the practice to provide the valve body 5, with a refill opening 14'. Said casing section 5 has an extension 15 on its lower end which is received

into the upper end of the hollow stand section 6, such extension being hollow and having the lower portion of its interior face suitably shaped to provide a valve seat 16. 5 At its upper end, said casing section 5 has a neck 17 and is provided with ribs 18, 18', the former of which has a pair of spaced apertured ears or lugs 19 and the latter of which has a pair of spaced upright standards 19' that extend upwardly for some distance above the ears or lugs 19.

10 A valve stem 20 is mounted for movement in the members 5 and 6, being provided with a body portion 21 which works in the section 5. The stem projects downwardly into the stand section 6 and carries a valve 22 which is preferably adjustably mounted for any desired adjustment of the valve with relation to its seat 16.

15 Pivotedly mounted in the ears or lugs 19 is one end of a lever 23 which is received through an opening 24 in the body 21 and also extending between and beyond the standards 19' with the other end thereof pivotally connected by a link 25 to the shorter arm 26 of an L-lever pivoted as at 27 in the standards 19'. The longer arm 28 of this L-lever is pivoted as at 29 to the upper end of a depending lever arm 30 having a link 31 on its lower end through which extends a set screw 32 that takes into the arm 28 and fixes the position of lever arm 30 with respect to the arm 28. The lever arm 30 is provided with an angularly extending socket 33, which receives the inner end of a float rod 34 that carries a float 35 of any desired form.

20 The valve 22 is adapted to engage the seat 16, and may be secured upon the stem in any desirable manner. In the present illustration, it is shown as being threaded on to said stem, and being held in adjusted position by means of nuts 22' on the stem above and below said valve respectively.

25 In practice, we have generally used the form of valve herein shown, though it will be obvious that a flat faced valve, with a valve seat to correspond, may be employed without in any wise departing from the spirit or scope of the invention. By adjustably securing the valve upon its stem, the same may be regulated so as to provide for any desired throw of such valve.

30 Carried by the body 21 so as to seat upon the upper end of the casing 5 when the valve is open, is a washer 36 which prevents any water that leaks along the stem squirting upwardly over the tank, any such leakage being projected laterally within the tank. 35 By this means we are enabled to dispense with stuffing boxes or other packing for the valve stem, which is usually a source of worry in connection with flush tank valves. The casing section 5 is secured to the stand

40 through lugs carried by the casing member into bosses of the stand section, a gasket 38 being provided between the members to effect a fluid tight connection.

45 Such being the construction, the operation of the device need it is thought be but briefly described as it is evident that when the flush valve (not shown) of the tank is opened, allowing the water in the tank to escape, the float 35 descends under the action 70 of gravity, rocking the lever arm 28 and lever arm 30 on pivot 27, and through the connections of lever arm 26, with the lever 23 tending to force the valve stem downwardly so as to unseat the valve 22 against 80 the pressure of the water supply, allowing water to flow into the tank, until such time as the float is again carried upwardly by the rising water to a position where the valve 22 seats, and where it is firmly held 85 against its seat by the pressure in the water supply.

50 The arm 26 is preferably provided with a plurality of openings so that adjustment may be made between lever 23 and lever 90 arm 28; adjustment may also be made of the valve 22, and also of the float by means of the set screw 32 and link 31, thus providing for any desired adjustment.

55 We desire to call particular attention to 95 the construction of the valve seat 16 and the valve 22. The valve seat is preferably made tapering as shown for the reason that we have found in practice that if the valve 22 goes against a blunt seat, the valve has 100 a tendency to rattle, whereas by providing the tapering seat, and a correspondingly-shaped valve, the seat forms a socket so that the valve pushes or pulls into the seat, gradually shutting off the pressure, and thus 105 obviating any "hammering" of the valve.

60 Having fully described our invention, what we claim as new and desire to secure by Letters Patent is;

65 1. In a ball cock valve in which the valve member opens against pressure and seats under pressure, a valve body embodying a casing section having a lateral discharge port and a downwardly projecting extension and a stand section receiving the extension 110 of the casing section, said extension having a valve seat on its lower end, a stem working in and extending through the casing section and projecting into the stand section, a valve adjustably connected to said stem for 115 engagement with said valve seat, a pair of standards carried by the casing section at one side of its upper end, a pair of lugs at the opposite side of said upper end of the casing section, a lever pivoted at one end to 120 said lugs and extending through said stem an L-lever pivoted between the upper ends of said standards, a link connecting the shorter arm of said L-lever with the free end 125 of said first mentioned lever, a lever-arm 130

pivottally connected at its upper end to the upper end of the long arm of said L-lever and adjustably connected at its lower end to said long arm intermediate the ends of the latter, and a float connected to the upper end of said lever-arm.

2. In a ball cock valve, a valve body comprising a casing section having a lateral discharge port and provided with an extension having a valve seat, a stand section receiving the extension of the casing section and to which the casing section is secured, a valve stem extending through the casing section and having an opening therethrough above the casing section, a valve on the stem within the stand section to engage said valve seat, a lever pivotally-mounted at one end on top and at one side of the casing section and extending through the opening in said valve stem, an L-lever pivotally-mounted on the top of the casing section at the opposite side of the stem, connections between the shorter arm of said L-lever and the other end of the first mentioned lever, a lever-arm pivotally connected at its upper end to the upper end of the longer arm of said L-lever and adjustably connected at its lower end to said longer arm intermediate the ends of the latter, and a float carried by said lever-arm.
3. In a ball cock valve, a body comprising a casing section having a lateral discharge

port and provided with an extension having a tapering valve seat on its lower end, a stand section receiving said extension and to which the casing section is secured, a valve stem extending through the casing section and provided with an opening above said section, a tapering valve on the stem within the stand section to engage said valve seat, a washer carried by the stem to seat upon the upper end of the casing section around the valve stem when the stem is in its lowest position, a lever pivotally-mounted at one end on the upper end of the casing section at one side of the valve stem and extending through the opening in said stem, an L-lever pivotally-mounted on the casing section at the other side of said valve stem, adjustable connections between the other end of said lever and the shorter arm of the L-lever, a lever-arm pivotally connected at one end to the longer arm of said L-lever and at its other end adjustably connected to said longer arm, and a float carried by said lever-arm.

In testimony whereof we affix our signatures in the presence of two witnesses.
